UNITED STATES PATENT OFFICE.

ALMERON H. PERRY, OF WASHINGTON, DISTRICT OF COLUMBIA.

SHOE-BAND.

1,326,687.

Specification of Letters Patent. Patented Dec. 30, 1919.

Application filed September 8, 1919. Serial No. 322,474.

To all whom it may concern:

Be it known that I, ALMERON H. PERRY, a citizen of the United States, residing at Washington, in the District of Columbia, 5 have invented a new and useful Shoe-Band, of which the following is a specification.

It is the object of this invention to provide a simple means whereby a shoe may be lifted or supported out of contact with a moist 10 pavement, and whereby a person may be prevented from slipping on a wet or icy surface.

In the drawing:—

Figure 1 shows the device in side elevation 15 applied to a shoe; Fig. 2 is a plan of the toe band; Fig. 3 is a fragmental bottom plan disclosing the tread; Fig. 4 is a section on the line 4—4 of Fig. 2.

The device includes a pair of strips preferably made of rubber, each strip being folded transversely as shown at 1 to form an eye 2. From the eye 2, the side portions of the strip diverge as shown at 3, and merge into parallel ends 4. Those portions of the parts 25 3 of the strip which are overlapped are connected as indicated at 5, by cement or otherwise, so as to fashion the eyes 2. The ends 4 of the two strips preferably but not necessarily are disposed in abutment as shown at 30 6, and are superposed on a tread 7 which may be made of rubber, the ends 4 of the strips being secured to the tread by cement or otherwise. The lower surface of the tread 7 is roughened at 8 in any desired way, so 35 as to prevent slipping. The eyes 2 carry separable fasteners 9, whereby the structure may be mounted on the toe of a shoe, as shown in Fig. 1. It is clear that the tread and the ends of the strips serve to elevate 40 the sole of the shoe out of contact with a wet pavement and operate, also, to prevent slipping. There is a distinct advantage in making the strips and the tread 7 in sep-

arate pieces, and in placing the ends 4 of the strips on top of the tread 7, since, owing 45 to this construction, the sole of the shoe is elevated not merely by a distance represented by the thickness of the tread 7, but by a thickness represented by the thickness of the tread plus the thickness of the ends 4. 50

If the device is to be applied to a heel, the tread 7^a has a heel-engaging flange 10 and is connected with bands constructed and mounted as hereinbefore described, numerals previously used being employed with the 55 suffix "a".

The invention is shown applied to a woman's shoe but is adapted to be used on an article of footwear of any sort.

I claim:—

1. A device of the class described comprising a pair of strips folded transversely to bring the ends of the strips adjacent to each other; a member whereon the ends of the strips are overlapped, said member forming a tread and forming a connection uniting the ends of the strips; and means for connecting the folded portion of one strip with the folded portion of the other strip. 60

2. A device of the class described comprising a pair of strips folded transversely to fashion eyes and to bring the ends of the strips adjacent to each other; a member whereon the ends of the strips are overlapped, said member forming a tread and 70 forming a connection uniting the ends of the strips; and separable fasteners mounted in the eyes. 75

In testimony that I claim the foregoing as my own, I have hereto affixed my signature in the presence of two witnesses.

ALMERON H. PERRY.
